UNITED STATES PATENT OFFICE.

PETER SWANSON AND AXEL CARLSON, OF ELY, MINNESOTA.

AUXILIARY CAR STEP.

1,425,149.

Specification of Letters Patent. Patented Aug. 8, 1922.

Application filed March 27, 1922. Serial No. 546,969.

To all whom it may concern:

Be it known that we, PETER SWANSON and AXEL CARLSON, both citizens of the United States, residing at Ely, in the county 5 of St. Louis and State of Minnesota, have invented certain new and useful Improvements in Auxiliary Car Steps, of which the following is a specification, reference being had therein to the accompanying 10 drawing.

This invention relates to auxiliary steps for a railway car platform, such as illustrated in our United States Patent No. 1,400,577 of December 20th, 1921, auxiliary 15 car-steps, and has special reference to an improved means for operating and controlling same.

The principal object is to provide a more simple, durable and effective means of this 20 character.

Other objects and advantages of the invention will appear in the further description thereof.

Referring to the accompanying drawings 25 forming part of this application in which like reference characters indicate like parts:

Figure 1 is a perspective view of the broken away lower portion of the vestibule of a railway car showing the under back 30 view of the steps into the vestibule with the auxiliary step and trap door of the vestibule open;

Figure 2 is an enlarged elevation of the operating and controlling mechanism, showing 35 portions of the vestibule and trap door in section, as well as the miter gears;

Figure 3 is an enlarged plan view of the trap door bolt in its door holding position;

Figure 4 is a similar view of the bolt in 40 its door releasing position;

Figure 5 is a plan view of the bolt operating mechanism; and

Figure 6 is a view similar to Figure 5 showing the connection of the hand operating 45 lever.

1 and 2 represent the opposite side walls of the ordinary steps into the vestibule of a railway passenger car, to the lower outer corners of which is pivotally suspended by 50 suitable arms 3 the auxiliary step 4, the arms 3 being pivotally attached to the rear-most corners of the step, as at 5, so that the step when lowered into receptive position for a pedestrian will occur in proper sequence with the stationary vestibule steps, 55 and, when folded upwardly and back-

wardly, will occur in close proximity to the under side of the lowermost stationary step. Spaced horizontal arms 6—6 are rigidly fixed to the rearmost edge of the step 4, extend rearwardly thereof, and are bent upwardly, as at 7, where they are pivotally connected, as at 8, to depending arms 9—9 bifurcated at their lower ends, rigidly fixed to the transverse rotatable shaft 10, which is suitably journalled, as at 11, upon the inner face of the step wall 2, and, at its opposite end, passes through the outer step wall 1; as at 12, where it is journalled within the two-part gear housing 13; the latter 60 being rigidly attached to the outer face of the step wall 1 by suitable bolts, as at 14.

Within the gear housing 13 and attached near the extreme end of the shaft 10 is the miter gear 15 meshing with a similar gear 16 attached near the end of the vertical operating shaft 17; the latter being journalled at its lower end within the housing 13. In this assembly we prefer to allow the extreme ends of both the shafts 10 and 17 to 70 extend within recessed portions within the housing, as illustrated at 18 for the shaft 10, and at 19 for the shaft 17, so that washers 20 may be employed adjacent both ends of the gear hubs, and in this manner provide for convenient adjustment of the gears by replacing or changing the thickness of the washers at the various places in order to accomplish the desired adjustment of the gears. 80

The gear housing 13 is made of two separate halves for convenience in assembly, and wholly encloses the gears to prevent obstruction by the elements and to permit of being filled with heavy grease, as is customary in similar devices. 90

The shaft 17 extends vertically upward through the deck 21 of the vestibule and adjacent the trap door opening 22 therein, where a washer or pedestal 23 is provided, 100 above which is rigidly fixed upon the shaft the door controlling crank arm 24. The shaft 17 continues on up to a suitable bracket 25 fixed to the inner side wall 26 of the vestibule and above which and onto the shaft is 105 fixed the operating lever holder 27 which pivotally carries, as at 28, the operating lever 29. Within the periphery of the bracket 25 are formed two notches 30 and 31, the latter being so positioned as to receive the operating lever 29 as it is allowed 110 to drop downwardly from the holder 27

when the step 4 is fully lowered for action, while when the shaft 17 is rotated for raising the step 4 the lever 29 will drop into the notch 30.

5 When the shaft 17 is thus rotated it is apparent that the same will impart reciprocal motion to the pitman 32 which is pivotally mounted, as at 33, in the bifurcated ends of the crank arm 24. The opposite end of 10 this pitman has an elongated slot 34 therein, through which is positioned the pin 35 of the crank arm 36 fixed to the short upright crank shaft 37 journalled within the rectangular shaft housing 38 of the door bolt 15 39; said housing being firmly attached to the deck 21 of the vestibule in any desired manner. The bolt 39 is provided with an integral upright shank 40 which extends longitudinally of the housing 38 and carries 20 thereupon an expansive spring 41 intermediate of the head of the bolt and the partition wall 42 within the housing so that at all times the tendency of the spring 41 is to keep the bolt extended. The extreme 25 inner end of the shank 40 is provided with a cross-head 43 against which the cam 44, fixed to the crank shaft 37, abuts, and whereby the bolt is withdrawn within the housing when the crank shaft 37 is properly rotated 30 for such purpose; the bolt being shown in this position in Figure 4 of the drawings, while it is shown extended in Fig. 3. At the upper end of the shaft 37 is mounted a suitable hand crank 45 by which the shaft 37 35 may be rotated at will, except when the trap door 46 is opened, when it would be impossible to operate the shaft 37 by hand in such a manner as to lock the trap door in closed position. However it may at times be 40 quite desirable to open the trap door when the auxiliary step 4 is not being used, and in which event the crank 45 may be employed for such purpose, the elongated slot 34 in the pitman 32 permitting of same; such independent manipulation of the trap door, of 45 course, only being possible when the hinged shaft 47 thereof is not directly connected with the main shaft 10, as illustrated, and in which event the trap door may be equipped with common spring hinges as is customary.

Having thus described our invention, what we claim as new and desire to secure by Letters Patent, is

1. Means for controlling the trap door 50 and auxiliary step of a railway car platform, said auxiliary step having a horizontally disposed shaft associated therewith, comprising a vertically disposed shaft extending upwardly above the platform of the car

and operatively connected with said horizontal shaft, means cooperatively connecting the horizontal shaft and the trap door, means at the upper end of the vertical shaft for manually operating same, and locking means for the trap door directly controlled 60 from the vertical shaft.

2. Means for controlling the trap door and auxiliary step on a railway car platform, said auxiliary step having a horizontally disposed shaft associated therewith, comprising 70 a vertically disposed shaft extending upwardly above the platform of the car and operatively connected with said horizontal shaft, means at the upper end of the vertical shaft for manually operating same, locking 75 means for the trap door directly controlled from the vertical shaft and means whereby the door can not be locked in its closed position when the auxiliary step is in its extended position.

3. Means for controlling the trap door and auxiliary step on a railway car platform, said auxiliary step having a horizontally disposed shaft associated therewith, comprising 80 a vertically disposed shaft extending upwardly above the platform of the car and operatively connected with said horizontal shaft, means at the upper end of the vertical shaft for manually operating same, locking 85 means for the trap door directly controlled from the vertical shaft, and said locking means having associated therewith a second manually controlled vertical shaft for unlocking the door when the auxiliary step 90 is not extended.

4. The combination with an auxiliary step and trap door for the vestibule of a railway car having a horizontally disposed operating shaft, of a vertically disposed shaft, the lower end of which is cooperatively connected with the outermost end of the horizontal shaft by means of bevelled gears, a two-part housing wholly enclosing the bevelled gears and forming bearings for the ends of the shafts, means at the upper 100 end of the vertical shaft within the vestibule for manually operating same, and means whereby the trap door of the vestibule may be controlled independently of the step controlling means.

In testimony whereof we hereunto affix our signatures in the presence of two witnesses:

PETER SWANSON
AXEL CARLSON
